Des. 185,576
Patented June 23, 1959

185,576

COMBINED CUTLERY HOLDER AND CUTTING BOARD

Leslie W. Seibert, Jr., Northbrook, Ill., assignor to Ekco Products Company, Chicago, Ill., a corporation of Illinois

Application November 23, 1955, Serial No. 39,023

Term of patent 14 years

(Cl. D58—12)

Fig. 1 is a front perspective view of a combined cutlery holder and cutting board embodying my new design;

Fig. 2 is a front perspective view thereof shown in closed position;

Fig. 3 is an end elevational view thereof; and

Fig. 4 is a top plan view thereof.

The rear face of the holder is plain.

I claim:

The ornamental design for a combined cutlery holder and cutting board, as shown and described.
